UNITED STATES PATENT OFFICE.

FRANK J. SCHOCH, OF GREENSBORO, NORTH CAROLINA.

WINDOW-SCREEN.

1,340,797.

Specification of Letters Patent. Patented May 18, 1920.

Application filed May 6, 1919. Serial No. 295,064.

To all whom it may concern:

Be it known that I, FRANK J. SCHOCH, a citizen of the United States of America, residing at Greensboro, in the county of Guilford and State of North Carolina, have invented new and useful Improvements in Window-Screens, of which the following is a specification.

This invention relates to window screens 10 of the class that are associated with spring rollers adapted to be wound about and unwound from the roller in a manner similar to a window shade or the like.

The invention aims to provide a bracket 15 of novel construction to accommodate both the window screen and shade, and to permit use of either one without in any way interfering with the other.

The chief characteristic of the invention 20 resides in the design of the bracket, wherein means is provided to close space between the bracket and screen, thus preventing flies or other insects from entering the room through the window; the bracket carrying 25 means controlling the movement of the screen in an upward direction, thus preventing the screen from being unduly wound about the roller should the screen slip from the handle while it is being raised.

30 The nature and advantages of the invention will be better understood when the following detailed description is taken in connection with the accompanying drawing the invention residing in the construction, 35 combination and arrangement of parts as claimed.

In the drawings forming part of this specification, like numerals of reference indicate similar parts in the several views and 40 wherein:

Figure 1 is a front elevation of a window, showing the invention applied thereto, and the screen secured in lowered position.

Fig. 2 is a vertical sectional view taken 45 therethrough.

Fig. 3 is a perspective view of the bracket.

Fig. 4 is a fragmentary horizontal sectional view through one of the guiding elements.

50 Fig. 5 is a detail view of the spring roller.

Fig. 6 is a view similar to Fig. 1, showing a modified form of the invention.

Fig. 7 is a fragmentary horizontal sectional view through one of the guiding elements.

In carrying out my invention, I provide a bracket including a body portion 10, adapted to be arranged transversely across the top of the window casing A, and secured 60 thereto in any suitable manner. Projecting forwardly from the opposite ends of the body portion 10, are the ears 11 and 12 respectively the former being provided with spaced parallel slots 13 opening at the edge 65 of the ear, while the ear 12 is provided with spaced openings 14 disposed in proper relation to the slots 13, so as to constitute bearings for the opposite ends of a window shade roller 15, and a screen supporting 70 roller 16. Both of these rollers are of the spring actuated type illustrated in Fig. 5. Upon reference to Fig. 2 it will be noted that the rollers 15 and 16 respectively are arranged in superimposed relation, the 75 roller 15 being disposed slightly in advance of the roller 16, to permit the use of either the shade 15 or the window screen 18 without one in anyway interfering with the other. When the screen 18 is lowered as 80 shown in Fig. 1, any suitable means may be employed for holding the screen in this position. As shown in Fig. 1, a sliding bolt 19 is adapted to be positioned within an opening in the lower end of the screen, to hold 85 the screen in lowered position, the bolt operating within a suitable casing or bracket 20 secured to the window casing. Secured to the opposite sides of the window casing are guiding elements or strips 21, which 90 as shown in Fig. 4 are bent away from the window casing to provide a channel in which the opposite longitudinal edges of the screen are received. As shown in Fig. 4, the sliding elements are slightly curved 95 as at 22 so that the free longitudinal edge of each element is arranged in close proximity to the screen 18 to present a neat appearance.

Projecting horizontally from the lower 100 edge of the body portion 10 of the bracket is a flange 23 having a width equal to the distance between the window casing A and the screen 18 so as to close the space between these parts, with a view of preventing 105 flies or other insects from gaining access to the room through the window opening. The disposition of the flange 23 in regard to the window casing and the screen 18 is clearly shown in Fig. 2. Depending from the flange 110 23 at the opposite ends thereof are lugs 24 which constitute stops to limit the upward

movement of the screen 18, and thus prevent undue winding of the screen about the roller 16, should the screen slip from the hand of the operator while being raised. The lugs 5 24 occupy a position in the path of the movement of the transverse reinforcing element 25 secured to the lower edge of the screen, and consequently when the element 25 is brought into engagement with the lugs 10 24 movement of the screen in an upward direction is positively checked.

In the modified form of the invention disclosed in Fig. 6, the bracket for supporting the screen roller is exactly the same as that 15 hereinabove described, and as shown in Fig. 3. However in this form of the invention, the guiding element 26 for the opposite longitudinal edges of the screen 27 is substantially U-shaped in cross section as shown in 20 Fig. 7. These elements may be secured to the frame A immediately adjacent the window sash, to permit the use of the screen on windows provided with shutters. As shown in Fig. 7, one of the limbs of the U-shaped 25 guide terminates in close proximity to the screen 27 to present a neat appearance. In this form of the invention, the screen 27 is maintained in its lowered position, through the instrumentality of the hooks 28 pivoted 30 upon the guiding elements 26, and adapted to engage in the eyes 29 carried by the lower edge of the screen. However, other suitable means may be employed for this purpose.

I desire to have it understood that what is 35 herein shown and described is merely illustrative, and that I do not limit myself to

the exact construction, and arrangement dis- 40 closed, inasmuch as such changes may be resorted to when desired as fall within the scope of what is claimed.

The bottom of the screen is provided with 45 a felt strip, to prevent the metal of the screen from coming in contact with the window sill, protecting the latter from being marred or otherwise injured.

What I claim is:—

1. As a new article of manufacture, a com- 50 bination window screen and shade roller bracket comprising an elongated body portion, ears projecting forwardly from the ends of said body portion and having spaced slots and openings, and lugs depending from 55 the lower edge of the body portion adjacent the opposite ends thereof, said lugs being offset forwardly of the body and constituting stops for the purpose specified.

2. As a new article of manufacture, a com- 60 bination window shade and screen roller bracket comprising an elongated body portion, ears projecting forwardly from the ends of said body portion and provided with spaced slots and openings, a horizontally ar- 65 ranged flange extended forwardly from the lower edge of the body portion, said flange having a width equal to the distance be- 70 tween the body portion of the bracket and said screen, and lugs depending from the forward edge of said flange and constituting a stop as and for the purpose specified.

In testimony whereof I affix my signature.

FRANK J. SCHOCH.
